UNITED STATES PATENT OFFICE.

PAUL STONER, OF WAYNESBORO, PENNSYLVANIA, ASSIGNOR TO LANDIS TOOL COMPANY, OF WAYNESBORO, PENNSYLVANIA, A CORPORATION OF PENNSYLVANIA.

MACHINE FOR GRINDING CRANK PINS.

Application filed January 13, 1922. Serial No. 528,999.

My said invention relates to a grinding machine intended primarily for grinding crank pins but not limited thereto, and it is an object of the same to provide a machine of the character described which shall have means for ready adjustment to grind pins of crankshafts of varying throw.

Another object is to provide means for quickly centering the individual crank-pins. 10 A further object of the invention is to provide an improved yielding bearing for the tail stock of the machine.

Other objects are to provide an improved work rest on which may be located an improved wheel truing device or a crank-pin centering device.

Referring to the accompanying drawings which are made a part hereof and on which similar reference characters indicate similar parts,

Figure 1 is a front elevation of the machine,

Figure 2 an enlarged view of the tail stock, partly in section,

Figure 3 an end view of the head stock crank carrying fixture,

Figure 4 a vertical section on line 4—4 of Figure 3,

Figure 5 a horizontal section on line 5—5 of Figure 3,

Figure 6 a face view of the tail stock crank carrying fixture,

Figure 7 a horizontal section on line 7—7 of Figure 6,

Figure 8 a vertical section on line 8—8 of Figure 6,

Figure 9 an end elevation of a work rest carrying a wheel truing device,

Figure 10 a plan view looking down from line 10—10 of Figure 9,

Figure 11 a section on line 11—11 of Figure 9,

Figure 12 a section on line 12—12 of Figure 9, and

Figure 13 is a detail view similar to Figure 9 showing a crank-pin centering device on the support in place of the wheel truing device.

In the drawings reference character A indicates the main frame of the machine on which are located a grinding wheel carriage B adapted to be moved longitudinally and transversely of the main frame, a head stock C and a tail stock D, together with various

other mechanisms forming no part of the present invention.

The head stock C carries a spindle driven by a pulley 20 and a head 21 having parallel flanges 22 on which is mounted a transversely slidable body 23 forming a support for a chuck 24. The slidable body 23 is held in place on the flanges by means of clamp bars 25 and bolts 26. A shaft 27 extends through a boss 28 integral with the body 23, the shaft and the boss being threaded and thus forming screw and nut gearing, and a pair of bosses 29 and 29' integral with the head 21. At one end the shaft has a head 30 and a collar 31 bearing graduations on its periphery. At the lower end the shaft extends through a washer 32 resting against boss 29'. A collar 33 is pinned to the shaft at 34 and a pair of locking screws 35 adapted to bear against the washer serve to hold the shaft against rotation and to take up any lost motion between the parts.

Tapering shims or wedges 36 are placed between the flanges 22 and overhanging parts of the body 23 to compensate for wear. The shim at the left side in Figure 3 is held in fixed position by a pin 37 threaded into a hole in the body 23 or otherwise fixed thereto. The right-hand shim is adjustable transversely of the head by means of a pair of set screws 38 and 39. The set screw 39 85 may be actuated to move the shim 36 upward to compensate for wear, the set screw 38 acting as a limit stop. When proper adjustment has been made by manipulation of the two set screws they are both set up 90 against the shim and mutually lock each other against rotation. A pair of limiting screws 40 are located to extend at their inner edge underneath the broad flat heads of screws 38 and 39 to prevent binding of 95 said screws and insure against possible distortion thereof.

The body 23 of the chuck-carrier has on its face a circular pad 41 with three holes 42 equally spaced from the center of the pad and from each other for attachment of a chuck having jaws 24', which may be a scroll chuck of ordinary type. The position of the jaws 24' is determined by the openings 42, the jaws of the chuck being arranged to hold the end of the crankshaft. The pad 41 is eccentrically located with reference to the body 23 and opposed thereto is

- 2
- a counterweight 43. If required a plurality of counterweights may be used as indicated in Figure 1, they being attached to the movable head by screws 41.
- 5 The tail stock is similar in structure to the head stock, its spindle having a fixed head 44 on which is mounted a transversely adjustable head 45 having a pad 46 with spaced openings, an adjusting screw 47 for 10 moving the adjustable head and its chuck transversely of the fixed head, and wedges 48 and 49 for taking up wear as in the head stock.
- 15 The tail stock has improved bearing devices for the spindle as shown in Figure 2. The spindle 50 is carried in a sleeve 51 having at its outer end an enlargement 52 in which is located a ball or roller bearing 53, the ball or roller bearing being in front of 20 an annular flange 54 on the spindle. At the rear of the flange is a bushing 55 in the bore of the sleeve which at the rear of the spindle is contracted to hold a nut 56 in rear of which the sleeve is again enlarged. The nut 25 56 is engaged by a left-handed screw thread at 57 on a rod or spindle 58 adapted at its inner end to enter an opening in the spindle 50. An abutment, here shown as a nut 59, surrounds the spindle 58 and has threaded 30 engagement with the frame of the tail stock.
- 35 A sleeve 60 rotatably mounted in the nut 59 has a spline engaging a groove in the rod 58 to permit the rod to slide through the nut. In front of the nut 59 is an externally threaded sleeve 61 having a flange at its rear end bearing against the nut 59 and carrying a nut 62 for adjustment of the tension of a spring 63 bearing at one end 40 against nut 62 and at the other against an annular flange 64 on rod 58. The function of this spring is to maintain a yieldable tension on the work carrying centers in doing ordinary grinding, the spindle 51 being then 45 replaced by an ordinary 60° work carrying center.
- 50 A slideable rod 65 having a handle portion 66 is mounted in the tail stock frame and its beveled forward end is adapted to engage a ring 67 on the fixed head of the rotary spindle to lock the device with the chuck holding jaws in uppermost position. A similar device for holding the front chuck in alignment with the rear one is shown 55 at 68.
- 60 Directly in front of the grinding wheel is located a support 69 or several such supports may be located at spaced intervals along the front side of the machine frame. This support has pivoted thereto an adjustably-mounted work-engaging device 70 and slidably mounted therein is a second work-engaging device 71. A screw shaft 72 having threaded engagement with the internally-threaded sleeve 76 serves to vary the posi-
- tion of the work rest 70. The sleeve 76 is held in place by a pin 77 against the force of a spring 75. The pin passes through a sleeve 79 held in adjusted position by set screw 80, and has a neck engaged by a leaf 70 spring 78 which normally holds the pin in locking position. In a cored-out recess of sleeve 76 is located a nut 73 having threaded engagement with shaft 72 and having a pin 73' engaging a groove in sleeve 76 to prevent relative rotation. A spring 74 in the recess back of nut 73 acts to take up wear on the screw-threads and to prevent rotation of shaft 72 due to vibration. A collar 81 having an extension with a hole engageable by a spring-pressed detent 82 prevents accidental rotation of the screw 72.
- 80 The rigid work rest 71 has a square head and a round stem 71' separate from the head and slidably mounted in the frame 69. The stem is held from rotating by a screw 83, so as to keep the long face of the rest against the work. At the rear end of the member 71' is a threaded rod 84 adapted for manual adjustment and normally held against rotation by a collar 85 having an opening engaged by a spring-pressed detent 86' (Figure 10).
- 85 At the top of the frame 69 is a fin 86 cut away to provide a rearward extension and also cut away at 88. In Figure 9 a wheel truing device is shown as mounted on this fin, the truing device comprising a curved frame 89 having a pair of downwardly extending flanges held in the proper relation 90 by a clamping screw 90 passing through them. A pin 91 engages under the rearward extension, the entire truing device being comparatively small and light so that a workman can pick it up and place it in position on the machine pushing it forward until the pin 91 engages underneath the extension 87. The truing device comprises a diamond holder 92 for a diamond 93 and operating and positioning devices therefor similar to 95 those disclosed in the patent to Shearer, 1,200,768, October 10, 1916.
- 100 Alternatively with the wheel truing device a crank-pin alining device may be positioned on the fin 86. The latter device has 105 depending flanges through which extends a pin 99. A spacer 100 is located between the flanges and about the pin 99 and the spacer has a flat forward face adapted to rest against the rear face of the fin 86. The body 101 of the aligning device has a slot at 102 for enabling the operator to grasp the device readily and to hold it in position. At 110 the forward end is a shaft 103 freely movable up and down and held from rotation by means of a spline at 104, said shaft having a pin 105 to limit downward movement. It will be obvious that a crankpin slightly 115 out of position will be aligned by the diverging lugs 106 on the shaft.
- 120
- 125
- 130

In the operation of my device a crank-shaft is located in the jaws of the left hand chuck, the right-hand chuck being retracted by means of the hand wheel 58' if necessary against the force of the spring 63. It will be seen that the sleeve 51 may be adjusted to vary the position of the chuck by turning the handwheel 58' and that said sleeve may also be forced out of its bearings to a considerable extent when removal of the sleeve is necessary by further rotation of the handwheel in a clockwise direction. When the crankshaft has been gripped by the jaws, the screws 27 and 47 are manipulated if necessary to center the crankshaft after which the aligning device 101 may be placed on fin 86 and the crank pins successively aligned in position to be ground. In a crankshaft for a six-cylinder engine two pins will be aligned simultaneously and the wheel may be moved from one to the other if desired so as to grind both of the aligned pins before again adjusting the crankshaft.

While I have illustrated and described a preferred form of my invention, it will be obvious to those skilled in the art that many modifications of said form may be made without departing from the spirit of the invention, and I desire to claim as my own all such modified forms, the true scope of the invention being indicated in the appended claims.

Having thus fully described my said invention, what I claim as new and desire to secure by Letters Patent, is:

1. In a crank grinder, means for supporting a crank shaft, a grinding wheel at one side of the crank shaft, a support at the other side thereof having an upstanding fin, said fin having a flat rear face and being undercut beneath said face and a crank aligning means adapted to rest on said support and having a face adapted to rest against the rear face of said fin, substantially as set forth.

2. In a crank grinder, means for supporting a crank shaft, a grinding wheel at one side of the crank shaft, a support at the other side, and a crank aligning device adapted to be positioned on said support, said device comprising a body and a vertically movable shaft slidable in said body, said shaft having diverging projections at its lower end, substantially as set forth.

3. In a crank grinder, head and foot stocks, radially adjustable chucks thereon, a Y-shaped crank-aligning device, and means to support the same in inverted position adjacent a crankshaft supported by said chucks, substantially as set forth.

4. In a crank grinder, head and foot stocks, radially adjustable chucks thereon, and a bifurcated crank-aligning device mounted for free movement radially of the crankshaft, substantially as set forth.

5. In a crank grinding machine, a pivoted work rest bearing against one side of a crank pin, a rotary threaded shaft bearing against the pivoted work rest, a sleeve having threaded engagement with the shaft said sleeve and shaft being slidable in unison on the machine frame, a spring bearing against the inner end of the sleeve, and means for holding the sleeve and shaft in place against the tension of the spring, substantially as set forth.

6. In a crank grinding machine, a pivoted work rest and means for adjustably supporting the same comprising a rotary shaft, a sleeve entering a chamber in the support, a spring within the chamber tending to force said sleeve and shaft away from said pivoted work rest, means to hold the sleeve in place, a nut also within the sleeve and having engagement therewith to prevent rotation of the nut and a spring between one end of the nut and the adjacent end of the sleeve, substantially as set forth.

7. In a grinding machine, a support, a pivoted work rest and means for adjustably supporting the same comprising a rotary shaft slidably mounted in a bearing on said support, a sleeve slidable in said bearing said sleeve having threaded engagement with the shaft, a detent for holding the sleeve in place, and means acting yieldingly on the shaft to prevent rotation thereof, substantially as set forth.

8. In a grinding machine, a pivoted work rest and means for adjustably supporting the same comprising a rotary threaded shaft, a nut therefor in a chamber on the support, a threaded sleeve entering the chamber and forming a nut for the shaft and having means to prevent rotation of the first-named nut, and a yielding detent engaging the sleeve to hold it in place, substantially as set forth.

9. In a grinding machine, a pivoted work rest, a shaft bearing at one end against said work rest, a sleeve slidable in a chamber on the machine frame with said shaft said shaft being adjustably secured to said sleeve, means to force the sleeve and shaft yieldably away from the work rest, and means for holding them in place against the action of said yieldable means, substantially as set forth.

10. In a grinding machine, a pivoted work rest, a shaft bearing at one end against said work rest, a sleeve slidable in a chamber on the machine frame with said shaft said shaft being adjustably secured to said sleeve, means to force the sleeve and shaft yieldably away from the work rest, means for holding them in place against the action of said yieldable means, and means acting yieldably on the shaft to prevent rotation thereof, substantially as set forth.

11. In a grinding machine, a pivoted work

rest, a rotary threaded shaft bearing against the tension of the spring, substantially as the pivoted work rest, a sleeve having set forth. threaded engagement with the shaft said In witness whereof, I have hereunto set 10 sleeve and shaft being slideable in unison on my hand at Waynesboro, Pennsylvania, this 5 the machine frame, a spring bearing against 31st day of December, A. D. nineteen hundred and twenty-one. holding the sleeve and shaft in place against

PAUL STONER.
